UNITED STATES PATENT OFFICE.

JOSEPH M. MILLER, OF CHICAGO, ILLINOIS.

FIRE-EXTINGUISHER.

SPECIFICATION forming part of Letters Patent No. 398,643, dated February 26, 1889.

Application filed January 23, 1888. Serial No. 261,689. (No model.)

To all whom it may concern:

Be it known that I, JOSEPH M. MILLER, a citizen of the United States of America, residing at Chicago, in the county of Cook and State 5 of Illinois, have invented certain new and useful Improvements in Fire-Extinguishers, of which the following is a specification.

Referring to the accompanying drawings, in which similar letters of reference indicate like 10 parts, Figure 1 is a side elevation of the entire apparatus; Fig. 2, a bottom view of the same; Fig. 3, a side and end view of the hand-discharge device; Fig. 4, a section and end view of the charging device; Fig. 5, a section 15 and end view of the automatic-discharge device in its normal condition; and Fig. 6, similar views of the same device, the section showing the parts at the moment of discharge.

This invention relates to that class of fire-extinguishers in which a portable vessel is charged with a fire-extinguishing solution under air-pressure and provided with means for discharging such fluid upon a fire by the force of the contained air-pressure. Structures of 20 this class have been already provided in some instances with an automatic discharge held normally closed by fusible solder, which melts at dangerous surrounding temperatures and allows the extinguishing-liquid to be sprayed 25 upon the fire, and in other instances with a discharge which can be opened by hand to allow the liquid to be directed upon a fire; but with a strong air-pressure operating continuously in the can it has been found almost 30 impossible to render it so perfectly air-tight as to enable the initial pressure to be maintained for a long time without material diminution. In the automatically-discharging cans no means has been provided for enabling the air-pressure to be tested from time 35 to time, so that the proprietor could see whether the apparatus could be relied upon for extinguishing a fire in the absence of an attendant, nor has such apparatus, so far as I 40 am aware, been constructed to discharge its contents both automatically and at the will of an attendant.

The objects of my invention are, first, to render such structures perfectly air-tight under heavy and long-continued internal air- 45 pressures; secondly, to enable the degree of contained air-pressure in an automatic-dis-

charge extinguisher to be conveniently ascertained from time to time, in order that its owner may know how far it can be relied upon 55 to do its work automatically in the absence of an attendant, and, thirdly, to adapt such structures to be operated both automatically and at will.

To these ends my invention consists, primarily, in combining the vessel with two discharge devices, one of which opens automatically through a sufficient increase in the surrounding temperature, and the other of which can at any time be opened and closed by 60 hand, and, secondarily, in the sub-combinations and structural improvements, more particularly indicated by the several claims here-to appended.

In the drawings, C is a can or portable tank, 70 of any preferred form and size, made of sheet-iron or other suitable metal, air-tight, capable of resisting any desired degree of contained air-pressure without leakage, lined in any suitable way to prevent corrosion, and provided with an ear, ring, or hook, c, at one end or side for suspending it from a cord, nail, or other support. This can is to be filled to about two-thirds of its capacity with a chemical fire-extinguishing solution of any approved 75 kind, and is then, by means of any suitable apparatus, to be charged with a sufficient quantity of air under strong pressure to force its liquid contents out and project them to a considerable distance when any of the discharge-ports are opened.

The charging device is represented at D, the automatic-discharge device at A, and the hand-discharge device at B. For the best results all three of said devices are arranged at 90 the end or side opposite to that at which the ear or ring c is applied, so that all the passages through which escape of air is ever possible shall be covered and sealed by the contained liquid when the can is in its normal 95 position. For the purposes of the main combination the two devices A B may be of any suitable construction, and it is immaterial that they are separate from each other or arranged at different points; but in each of 100 said devices, as well as in the device D, the passage or port must be normally closed with a valve of soft rubber or other equivalent soft, flexible, elastic material impervious to air,

and not liable to corrosion from the chemical solutions contained in the vessel, and such valve must be forced strongly against its seat and locked or otherwise held there, so that it

5 cannot unseat except for the performance of its appropriate functions. Each of the valved passages, wherever possible, is further guarded by an additional screw-plug or soldered cap, or both. The conjoint effect of 10 these several provisions is to render the vessel so absolutely air-tight that its internal pressure is maintained undiminished for any length of time, and it is always in condition for effective use.

15 The specific construction of the several devices A B D employed by me is as follows: Referring to the filling device D, I construct this in the form of a metallic tube or capsule, *d*, the inner end of which is closed by a perforated plate, *d'*, upon which rests a soft, elastic, flexible valve, *d*², secured to the plate *d'* at its center by a pin, *d*³, and provided with a rigid central plate, *d*⁴, held to it by said pin, so as to render the center of the valve rigid 25 and leave only its edges flexible. This valve, which acts as a check-valve, will yield for the admission of the liquid and air under pressure through the tube *d*, but under the back-pressure of the air so admitted will seat firmly 30 upon the end plate, *d'*, preventing any escape backward. For additional security, however, I close the outer end of the tube *d* with a close-fitting internal screw-plug, *d*⁵. There is no possibility of the escape of air or liquid 35 through the device when so constructed. The tube *d* is soldered or brazed into the bottom of the can.

Referring to the automatic-discharge device A, I construct this in the form of a shouldered tube, *a*, soldered or brazed into the bottom of the can, and provided with an internal flange, *a'*, at its inner end. Within this tube I arrange a sliding tube, *a*², having at its lower end a perforated rose-head, *a*³, or a deflector of any approved form, and at its upper end an external flange, *a*⁴, to prevent its escape from the tube *a*. In the larger outer end of the tube *a*, I insert a thick close-fitting disk, *a*⁵, of soft, flexible, elastic material, which 45 seats air-tight up against the internal shoulder, *a*⁶, of said tube, and I provide a plug or cap, *a*⁷, which is inserted into the outer end of the tube, pressed firmly up against the disk *a*⁵, so as to hold the latter tightly to its 50 seat, and soldered to the tube *a* with fusible-alloy solder, melting, preferably, at about 155°, Fahrenheit. The valve *a*³ keeps the liquid away from the fusible-solder joint, and prevents any chilling of the latter until the cap 55 has been entirely discharged from the tube, and by its elastic force it aids the internal pressure (which acts through the sliding rose-head *a*³) in forcing the cap out of the tube when the solder melts. When the valve and 60 cap are out, the sliding rose-head *a*³ projects from the outer end of tube *a*.

65 Referring to the hand-discharge B, I first

solder or braze into the can a tubular metal plug, *b*, provided with screw-threads. Into this I insert a tubular discharge-stem, *b'*, the inner end of which preferably reaches nearly to the opposite side of the can, as shown in dotted lines in Figs. 1 and 2, and attach this tube to the plug *b* by means of threads *b*², which screw into the threads of the former. I screw 70 the shoulder *b*³ up against the end of the plug *b*, and cover the joint with solder, so as to prevent any escape of air at that point. The outer end of the tube *b'* is enlarged, and a portion of it cut away to accommodate a 75 swinging block, *b*⁴, which is pivoted to the main stem at *b*⁵, and is provided with a swinging link or strap, *b*⁶, carrying a setscrew, *b*⁷, by which to lock and tighten up the block against the body of the discharge device, as shown in Figs. 1 and 3. The inner end of the block *b*⁴ inclines, preferably, at an angle of about forty-five degrees, and is provided with a plate or block of soft rubber, *b*⁸, secured to it by a wire, *b*⁹, or by cement or other suitable 90 means, which rubber plate fits air-tight against an inclined shoulder, *b*¹⁰, upon the tube *b'*, when the block is locked in the position shown in Fig. 3. The central bore of the stem *b'* contracts to a discharge-nozzle at this 95 point, as shown in dotted lines in Fig. 3, so as to be opened when the block is released, as shown in dotted lines in Fig. 1, and closed air-tight at all other times.

This improved structure, as a whole, is designed to be suspended at a proper elevation and position in the room to be protected, where in the absence of an attendant it will operate automatically to spray water upon any accidental fire in consequence of the melting of 100 the fusible solder by the rise of temperature occasioned thereby. It is also adapted, in case the fire occurs when an attendant is near, to be conveyed to the immediate neighborhood of the fire and opened by hand to direct the 105 extinguishing-liquid in a concentrated stream upon the exact point where it is most needed, and thus extinguish the fire more quickly than could be done by the spraying rose-head and with greater economy of the chemical solution. The hand-discharge B can be opened 110 and closed very quickly, from which results the great advantage that it can be used at any time as a petcock to test the degree of effective pressure in the can in case a suspicion 115 should arise that it has not been properly filled or that leakage of air has occurred, thus enabling the proprietor to inform himself at any time of the exact extent to which he can rely upon his fire-extinguisher for protection, 120 and to remedy any defective pressure in season, in which respect this part of the structure acts as the practical equivalent of a pressure-gage, but is much cheaper and less liable to become accidentally damaged. The stem *b'* 125 is preferably extended across nearly to the opposite side of the can, so that in case the operator should desire to elevate the hand-discharge nozzle to give the discharging stream 130

a greater range the liquid will cover the end of the tube until it is substantially exhausted from the can.

Having thus described my invention, I claim

5 as new—

1. The combination, with a portable fire-extinguisher consisting, essentially, of an air-tight receptacle or can containing a fire-extinguishing liquid and air or gas maintained 10 under pressure and provided with a discharge-valve adapted to be operated by hand, and a supplemental discharge-valve applied at or near the base of the can and adapted to be released by an increase in temperature, whereby 15 said receptacle is adapted for use as a portable extinguisher or as a stationary extinguisher by suspending it over or near the place to be protected, the hand-operated valve serving a double purpose to discharge the 20 contents and test the pressure, substantially as described.
2. In a fire-extinguisher such as described, the combination of the tube b' , containing the discharge-orifice, the block b^4 , carrying the 25 packing or valve, and the link to which the fastening for engaging the tube is attached, said block b^4 being pivotally attached to the tube and swinging down to clear the discharge-orifice when the link is disengaged 30 from the tube, substantially as described.
3. In a fire-extinguisher, the combination of the shouldered tube a with a sliding internal tube, a^2 , provided with a spraying device at

its outer end, and with a soft elastic block or disk, a^5 , which closes the tube a and against 35 which said spraying device normally rests, and the retaining cap or plug, a^7 , secured in the tube a by fusible solder, substantially as described.

4. In a fire-extinguisher, the combination of 40 the discharge-tube b' with the rubber valve b^8 , the pivoted block b^4 , for forcing the valve to its seat, the freely-swinging link b^6 , and the set-screw b^7 , for tightening the pressure upon the valve while permitting of its rapid opening, substantially as described.

5. The combination, to form a portable fire-extinguisher such as described, of an air-tight can or receptacle provided with inlet and two outlet orifices, the one closed by a hand-operated valve and the other by an automatic valve released by an increase in temperature, all of 50 said orifices being located at or near the base of the can or receptacle, which latter is charged with a fire-extinguishing liquid and a volume 55 of air or gas under pressure, whereby all the orifices being below the liquid the escape of air or gas is prevented, and should the orifices be imperfectly closed the liquid in escaping 60 will indicate the fact that the apparatus is not in perfect order and requires attention.
